UNITED STATES PATENT OFFICE.

RANDOLPH REHRAUER, OF TWO RIVERS, WISCONSIN.

RAIN-TROUGH SUPPORT.

1,272,527.

Specification of Letters Patent. Patented July 16, 1918.

Application filed July 18, 1917. Serial No. 181,199.

To all whom it may concern:

Be it known that I, RANDOLPH REHRAUER, a citizen of the United States, and resident of Two Rivers, in the county of Manitowoc and State of Wisconsin, have invented certain new and useful Improvements in Rain-Trough Supports; and I do hereby declare that the following is a full, clear, and exact description thereof.

10 My invention relates to certain new and useful improvements in means for supporting rain troughs or spouts, and has for its primary object to dispense with the usual and faulty arrangement now employed for 15 supporting rain troughs which consist of a strip of tin passing around the under portion of the trough and having its ends nailed to the roof eave.

A further object is in the provision of a 20 one piece spring metal support which has a portion bent to conform with the curvature of a rain trough and has its stop portion flat with suitable attaching means carried thereby.

25 A still further object is in the provision of novel means for attaching or detachably securing the support upon the spout in such a manner as to prevent removal thereof when the trough is filled with water.

30 With the above and other objects in view which will appear as the description proceeds, my invention resides in the novel construction, combination and arrangement of parts substantially as hereinafter described and particularly defined by the appended claim.

In the accompanying drawings I have illustrated one complete example of the physical embodiment of my invention constructed according to the best mode I have so far devised for the practical application 40 of the principles of my invention, in which:—

Figure 1 is a transverse sectional view 45 through a rain trough with my invention applied thereto and illustrated in elevation.

Fig. 2 is a top plan view thereof, the supporting frame being partly broken away 50 and the rain spout being illustrated by dotted lines, and

Fig. 3 is a sectional view taken on the line 3—3 of Fig. 1.

Referring now more particularly to the

drawing, in which similar reference numerals designate like parts throughout the several views, 5 designates the conventional rain trough which is semicircular in cross-section and has its outer end beaded as at 6 and my invention is adapted to engage the trough and to be secured to the roof eave in a manner similar to that of securing the thin metal strip now universally used for this purpose. 55

This hanger is made of any spring metal such as wrought iron, steel or the like and has its bottom or strap portion curved as at 7 and its outer side curved as at 8 in order to form a trough receiving portion as 70 shown in Fig. 1. The top or bridge portion 9 of the hanger extends across the trough from the beaded portion 8 and has its end down-turned and curved to conform with the curvature of the inner wall of the 75 trough as at 10, and provided in the bridge portion near the end 10 is an aperture 11 for receiving the down-turned tongue 12 formed on the other end of my device.

The trough-hanger is supported by a 80 bracket 13 having an upper arm 14 for engagement with the roof eave (not shown) and a perforated foot 15 of the bracket is fitted to the bridge 9, there being a slot 17 formed in the bridge for the reception of a 85 bolt 16 whereby the parts are secured.

From the foregoing description taken in connection with the accompanying drawing, it will be obvious that to secure my device to a rain trough, the tongue 12 is disengaged from the aperture 11 and the device sprung apart and slipped upon the trough when the tongue 12 is again engaged in the opening 11, the bracket 13 having its arm 14 supported from the roof eave in any desired manner. 90

In most devices of this character, the support, when the trough is filled with water, breaks apart and allows the trough to drop, but by my invention, the greater the stress 100 the more securely the trough is secured in the holder or support. This is attained by having the end 10 retain the trough between its outer wall and the inner wall of the corresponding side of the bottom portion 7. As will be seen when the trough is filled with water, the strap portion 9 will tend to buckle outwardly, drawing inwardly 105 the ends of the support, thus forming vise

like jaws with the end 10 and the corresponding surface of the strap portion 7 between which the trough is securely clamped.

What is claimed is:—

5 The combination with an eaves trough semi-circular in cross section, of a hanger therefor comprising a strap portion disposed about the outer wall of the trough and conforming closely to the contour
10 thereof, one end being extended beyond the adjacent edge of the trough and bent laterally over the open top thereof to engage said edge, a down-turned tongue extending into the trough at right angles to said laterally bent end, a bridge portion of sheet material connected at one end with the other end of the strap portion, the free end of the bridge portion being disposed adjacent said tongue and laterally and down-
15 wardly turned to form a foot, the other part being substantially straight, said foot be-
20

ing curved for engagement with the inner wall of the trough, said bridge portion having a hole spaced from the free end of the straight part thereof, or from said foot, a 25 distance substantially equal the length of the laterally bent end of the strap portion whereby when said tongue is inserted through said hole, the foot will be drawn toward the adjacent part of the strap portion and the upper edge of the trough firmly gripped therebetween, the bridge portion thus constituting in connection with the strap portion a reinforced stay for the trough in opposition to inward and outward strain. 30

35 In testimony that I claim the foregoing I have hereunto set my hand at Two Rivers, in the county of Manitowoc and State of Wisconsin.

RANDOLPH REHRAUER.
